UNITED STATES PATENT OFFICE.

WILLIAM H. FAUBER AND ALBERT M. PRICE, OF CHICAGO, ILLINOIS.

DESIGN FOR A CRANK-ARM FOR VELOCIPEDES.

SPECIFICATION forming part of Design No. 32,700, dated May 22, 1900.

Application filed April 20, 1900. Serial No. 13,673. Term of patent 14 years.

To all whom it may concern:

Be it known that we, WILLIAM H. FAUBER and ALBERT M. PRICE, citizens of the United States, residing at Chicago, in the county of Cook and State of Illinois, have invented and produced a new and useful Design for a Crank-Arm for Velocipedes, of which the following is a specification, reference being had to the accompanying drawings, forming part hereof.

As shown in the drawings, Figure 1 is a side elevation of a crank-arm embodying our design. Fig. 2 is an edge view of the crank-arm. Fig. 3 is an inside elevation thereof.

The leading or characteristic features of the crank-arm made in accordance with our design are as follows:

The crank-arm is made smaller at its outer than at its inner end, where it joins the crank-shaft, and tapers from its inner to its outer end. The outer side or face of said arm is composed of three plane surfaces—namely, an intermediate surface and two exterior or lateral surfaces. Said intermediate surface is widest at the outer end of the arm, extending the full width of the arm at the said outer end thereof, and tapers gradually toward the inner end of the arm. At said inner end of the arm the margins of said intermediate surface are brought together, or nearly so. The lateral or exterior flat surfaces of the arm are oblique with respect to the central intermediate surface thereof, are arranged symmetrically on either side thereof, are widest at the inner end of the arm, and taper gradually toward the outer end thereof, where their side edges meet, or nearly so, in the plane of the side or edge faces of said arm. The side margins of said lateral oblique surfaces meet or coincide with the side margins of the intermediate surface, so as to form two angles at either side of said intermediate surface, extending the full length of the crank-arm.

The side faces or edges of the arm are each provided with flat or plane surfaces extending the full length thereof. Said flat edge 45 surfaces are widest at the outer end of the arm, where they are equal in width to the thickness of the arm, and taper from the outer to the inner end of the arm, where their side edges meet or nearly meet. The outer side 50 margins of said flat edge surfaces meet or coincide with the outer margins of the oblique flat surfaces of the outer face of the arm, so as to form two angles at either side of said outer face, extending the full length of the 55 arm.

On its inner face the arm is convexly rounded, with a varying degree of convexity from its outer to its inner end. At its outer end it is flat or only slightly rounded, while at its 60 inner end, adjacent to the shaft, said inner surface has a maximum degree of convexity. The rounded inner face of the arm intersects at its wide margins the flat tapered edge surfaces thereof at angles to the latter, meeting 65 the inner tapered or oblique margins of said side or edge faces at well-defined angles, so that the said flat edge faces are clearly and accurately defined.

The rounded inner surface of the arm intersects the cylindric surface of the shaft and is joined or merges into said cylindric surface. 70

What we claim as new is—

The design for a crank-arm for velocipedes 75 substantially as herein shown and described.

Signed at Chicago, Cook county, Illinois, on the 10th day of April, A. D. 1900.

WILLIAM H. FAUBER.
ALBERT M. PRICE.

In presence of—

GERTRUDE BRYCE,
DOROTHY MARION.
